TANDEM CONTROL FOR PRESSING MACHINES

George W. Johnson, Cincinnati, Ohio, assignor to
The American Laundry Machinery Company,
Norwood, Ohio, a corporation of Ohio

Application April 5, 1935, Serial No. 14,790

12 Claims.

(Cl. 68—9)

This invention relates to an improvement in control mechanism for pressing machines such as are generally in use for laundry and garment work. More particularly the invention relates to a tandem control for a plurality of machines. It is customary in laundries to operate pressing machines in pairs, attended by one operator. It is also customary to connect such a pair of machines for tandem control, that is to say, the control mechanism is arranged so that the operator working at one machine upon closing it is able to actuate the opening mechanism of the other machine so that the pressing members have separated and the steam and heat have somewhat dissipated before she arrives at that machine to remove the finished work. Heretofore it has been customary in such tandem control mechanism to provide an additional manual or other device actuated by the operator at one machine to cause the opening movement at the other machine. Inasmuch, however, as the automatic operation is the usual one, my invention discloses control mechanism, the usual operation of which to produce closing of one machine will also produce opening of the other machine. My improved control mechanism, however, also provides additional means operable to disable the tandem connection so that each machine may be operated independently if desired. My invention resides in the novel association of the control mechanisms of two pressing machines as more fully set forth in the specification and the accompanying drawing.

The drawing represents a pair of pressing machines in end elevation and partly in section with the control mechanism diagrammatically arranged.

For ease of description I have designated the two pressing machines A and B respectively and since they are alike one only will be described and similar numerals will be applied to the other with the prime suffix.

For illustrative purposes I have shown my invention as applied to pressing machines of the type illustrated, described and claimed in the copending application of John P. Singiser, Ser. No. 642,053, filed November 10, 1932. This copending application discloses a frame 10 supporting a stationary pressing bed 11 and pivotally supporting also on a bracket of the frame a head lever 12 which carries a pressing head 13 adapted to contact with the bed. The head is biased toward open position as shown in press B by a spring 14 connected between the rear end of the head lever 12 and the frame. The head is moved into pressing

engagement with the bed by means of a toggle 15 which is moved from broken toward straightened position to close the head upon the bed. For so moving the toggle a fluid actuated cylinder and piston motor 16 is provided having a piston 17 whose piston rod 18 is connected to the toggle knuckle. Motive fluid is supplied to motor 16 through conduit 19, check valve 20, port 21, valve casing 22 and passage 23. Valve casing 22 houses a reciprocating piston valve 24 having a stem 25 extending rearwardly through the valve casing. A spring 26 normally biases the valve toward the front of the press as shown in press B, which establishes communication from motor 16 through passage 23 to exhaust port 27 so that motor 16 is normally open to atmosphere. When motive fluid is supplied through conduit 19 from a suitable source, piston valve 24 moves to the position shown in press A thus closing the exhaust port and permitting pressure fluid to enter motor 16 through passage 23 to cause a working stroke of the motor. Moving in unison with the piston rod 18 is a cam 28 having a depressed portion 29 in which a follower 30 is adapted to drop biased by a spring 31 when the press is substantially completely closed. This establishes a fluid maintaining circuit which maintains the press closed under pressure. The connections for establishing this circuit comprise a bellcrank 31, one arm of which carries the follower 30 and an upstanding arm 32 of which engages the stem 33 of a normally closed inlet valve 34 which is housed in a valve casing 35 and supplied with motive fluid through a suitable conduit 36. This mechanism opens valve 34 when follower 30 drops into the depressed portion of the cam 28 and permits motive fluid to pass through conduit 37 to passage 23 which serves to retain valve 24 in the position shown on press A and holds piston 17 at the outermost point of its stroke so that the press remains closed under pressure.

The release mechanism comprises a treadle 38 pivotally mounted on the frame and biased in its upward position by a spring 39. The treadle is connected by a link 40 with a bellcrank 41 which has an upstanding arm 42 which lies opposite the valve stem 25 and in position to abut and move the same upon depression of the treadle and rotation of bellcrank 41 in a clockwise direction as seen at press A. At the same time, the arm 42 of the bellcrank is adapted to engage a projection 43 on bellcrank 31 to rotate the bellcrank in a clockwise direction about its pivot 44 thus permitting valve 34 to return to its normally closed position under the influence of its spring. This

cuts off the supply of motive fluid to motor 16 and opens the same to exhaust port 27 whereupon spring 14 is effective to reopen the press.

The purpose of check valve 20 is to prevent back flow through conduit 19 after the press is fully closed and the maintaining circuit is established.

Power means is provided to actuate the treadle 38 and the form shown comprises a small fluid motor 45 whose piston 46 has a stem 47 adapted to coact with the upstanding arm 43 of treadle 38 so as to move the treadle in a clockwise direction about its pivot. The piston is biased toward inoperative position by a spring and is supplied with motive fluid through a suitable conduit 49. The piston 46 is sufficiently loose-fitting to permit its return movement by its biasing spring.

My improvement comprises a novel interconnection of the control mechanism for two such presses as shown in the drawing. For the supply of motive fluid to motor 16 I provide two normally closed inlet valves in series 50 and 51 with a supply conduit 52 communicating with the main conduit 36 and a conduit 53 connecting the two valves in series. Valve 50 is actuated by manual 54 and valve 51 by manual 55 and it will be evident that actuation of both manuals simultaneously will supply motive fluid to conduit 19 and motor 16 as previously described.

Means is provided whereby the normal actuation of the control means for press A energizes the power actuator for the release means of press B. The present embodiment comprises a conduit 56 branching from conduit 19 and leading through valve casing 57 to conduit 49' to supply motive fluid to release motor 45' of press B. In valve casing 57 is a normally open valve 58 which is actuatable by a manual 59. This valve casing 57 might be a separate device from the control means for motor 16 but preferably it is grouped with one of the inlet valves for motor 16 so that manual 59 and one of the two-hand controls, in the present instance 55, may be grasped by one hand of an operator when desired.

In the normal operation of the machines A and B in tandem, with press A open and press B closed, the operator would arrange the lay of the work upon the bed 11 and actuate manuals 54 and 55. This would supply motive fluid to motor 16 which would close the press as already described and when the press is finally closed the interconnecting parts will establish the fluid maintaining circuit to keep the press closed under pressure. Simultaneously with the flow of motive fluid through conduit 19 to motor 16 for the purpose of closing press A motive fluid will pass through conduit 49' to motor 45' of press B. This will cause a stroke of piston 46' causing the stem 47' to engage the arm 48' of treadle 38' which will oscillate the treadle in a counterclockwise direction about its pivot thus pulling downwardly upon link 49' which in turn will cause bellcrank 41' to rotate in a counterclockwise direction so that arm 42' engages stem 25' and moves valve 24' to the position shown at press B. Simultaneously, arm 42' engages the projection 43' of bellcrank 31' to move the latter bellcrank in a counterclockwise direction against the bias of spring 31b which will permit valve 34' to be seated under the influence of its spring. This cuts off the flow of pressure fluid to motor 16' and opens the same to exhaust at port 27' whereupon spring 14' moves press B to open position. The operator then moves to press B, removes the finished work thereupon and actuates manuals

54' and 55' whereupon press B closes and motive fluid passes through conduit 49 to motor 45 to open press A.

The above is the normal operation of two pressing machines but when the operator desires to operate one press alone, say for instance press A, she actuates manual 54 but simultaneously grasps manuals 55 and 59 so as to actuate valve 51 to open position and valve 58 to closed position, thereupon press A is actuated but nothing happens at press B as no fluid can reach conduit 49'.

What I claim is:

1. In combination, two independently operable presses, power means for closing each press, power actuated release means for causing opening of each press, control means for each press-closing means, means normally effective upon actuation of said control means at a first of said presses to energize said release means at the second of said presses, and a manually controlled device at said first press for disabling said last named means.

2. In combination, two independently operable presses, power means for closing each press, power actuated release means for causing opening of each press, two-hand operated control means for each press-closing means, means normally effective upon actuation of said control means at a first of said presses to energize said release means at the second of said presses, and a manually controlled device at said first press for disabling said last named means.

3. The combination of claim 2, and in which said manually controlled device is grouped with one part of said two-hand operated control means of said first press for simultaneous operation by one hand of the operator.

4. In combination, two independently operable presses, power means for closing each press, means for maintaining each press closed, power actuated means for releasing each maintaining means, control means for each press-closing means, means normally effective upon actuation of said control means at a first of said presses to energize said release means at the second of said presses, and a manually controlled device at said first press for disabling said last named means.

5. The combination of claim 4, and in which said control means includes spaced manuals operable by the two hands of an operator, and said manually controlled device is grouped with one of said manuals by simultaneous operation by one hand of the operator.

6. In combination, two independently operable presses, fluid power means for closing each press, means tending to open each press, fluid actuated release means for causing opening of each press, fluid supply means for each power means, open conduit means extending from said fluid supply means at a first of said presses to said release means at the second of said presses, a normally open valve in said conduit means, and a manual at said first press for closing said valve.

7. In combination, two independently operable presses, fluid power means for closing each press, means tending to open each press, fluid actuated release means for causing opening of each press, fluid supply means for each power means including spaced manuals operable by the two hands of an operator, open conduit means extending from said fluid supply means at a first of said presses to said release means at the second of said presses, a normally open valve in said conduit means, and a manual at said first press for closing said valve.

press for closing said valve, said last named manual being grouped with one of said spaced manuals for operation by the same hand of an operator.

5. 8. In combination, two independently operable presses, power means for closing each press, operator actuated means for causing opening of each press, a power actuator for each operator actuated means, control means for each power means, means normally effective upon actuation of said control means at a first of said presses for energizing said power actuator at the second of said presses, and a manually controlled device at said first press for disabling said last named means.

10. 9. In combination, two independently operable presses, power means for closing each press, operator actuated means for causing opening of each press, a fluid actuator for each operator actuated means, control means for each power means, means connected with said control means of a first of said presses and normally effective to supply pressure fluid to said actuator at the second of said presses by operation of said control means at said first press in press-closing-producing direction, and a manually controlled device at said first press for disabling said last named means.

15. 10. In combination, two independently oper-

able presses, fluid power means for closing each press, operator-operated release means for causing opening of each press, a fluid actuator for each release means, fluid supply means for each power means including two spaced safety manuals, open conduit means extending from said fluid supply means at a first of said presses to said fluid actuator at the second of said presses, a normally open valve in said conduit means, and a manual at said first press for closing said valve.

11. The combination of claim 10, in which said last named manual is grouped with one of said spaced safety manuals for grasping of both manuals by one hand of an operator.

15. 12. In combination, two independently operable presses, fluid power means for closing each press, means actuated upon closing of each press for maintaining that press closed, operator-operated release means for each maintaining means, a fluid actuator for each release means, fluid supply means for each power means including two spaced safety manuals, open conduit means extending from said fluid supply means at a first of said presses to said fluid actuator at the second of said presses, a normally open valve in said conduit means, and a manual at said first press for closing said valve.
